THOMAS E. BROWN, JR., OF YONKERS, WILLIAM G. WILLIAMS, OF NEW YORK, AND SHORTRIDGE HARDESTY, OF BRONX, NEW YORK.

OPERATING MECHANISM FOR MOBILE BRIDGES AND THE LIKE.

Application filed December 19, 1924. Serial No. 756,879.

In raising and lowering the pivoted spans of bascule bridges it is common to use a pinion operating a rack which is connected to the bridge by a simple strut, which rocks about the pinion as its outer end moves up or down with the bridge; and it is common to use a more or less complicated rocking frame to guide the strut and hold it in proper engagement with the pinion. Similar conditions apply to rack and pinion operating mechanisms for other types of moving structures.

Our present invention aims to provide an operating mechanism of this class which has advantages chiefly in the direction of simplicity, compactness and economy as compared with previous designs.

The accompanying drawings illustrate embodiments of the invention applied to a well-known type of bascule bridge.

Fig. 1 is a side elevation of the bridge and operating mechanism;

Fig. 2 is a plan illustrating the operating mechanism at one side;

Fig. 3 is an enlarged detail of Fig. 1;

Fig. 4 is a side elevation of the pinion and immediately adjacent parts;

Fig. 5 is a side elevation of the strut, reduced in the longitudinal dimension so as to show more clearly the variation in the top surface;

Fig. 6 is a cross-section, partly in elevation, of the pinion and immediately adjacent parts;

Figs. 7 and 8 are vertical sectional views through the pinion illustrating modified constructions;

Fig. 9 is a longitudinal-sectional view on the line 9—9 of Fig. 10; and Fig. 10 is a cross-section on the line 10—10 of another modification.

Generally, bridges of this character will be provided with an operating mechanism for each side or truss of the bridge. We will describe the mechanism for one side only.

In Fig. 1 the truss 1 is mounted at one end on a horizontal pivot 2 carried at the end of a fixed frame or tower comprising a base 3, a vertical member 4 and an oblique member 5 and a strong strut or diagonal brace 5^a. The weight of the truss is carried through links 6 and 7 to a beam 8 pivoted on top of the stationary frame and carrying at its outer end a counterweight 9. The oper-

ating mechanism comprises a motor 10 which through suitable gearing drives the pinions 16 which move the truss. The motor is located substantially at the sidewalk level so as to be readily accessible and at the side of the roadway so as not to interfere with traffic. At the apex of the first panel of the truss there is pivotally connected a strut or other connecting member designated as a whole by the number 11 and which carries racks in engagement with pinions driven by the electric motor.

As indicated in Figs. 3 and 6, the operating member includes two pairs of channels 13, the channels of each pair being connected together at intervals by spacers 14 and each pair being located on one side of the member 5^a of the supporting frame. A rack 15 is mounted in the lower part of the space between each pair of channels. There are thus two racks arranged parallel to each other on opposite sides of the fixed frame (which is in substantially the same plane as the truss) and there are two pinions 16, one for each of these racks. The principle is the same, however, as if there were a single connecting member and rack operated by a single pinion. The two pinions are keyed on a shaft 17 one end of which is mounted in a bearing 18 on a frame 45 which may be supported in any suitable manner. The shaft 17 carries a gear 20 driven by a pinion 21 on a shaft 22 supported by a standard 19 and carrying a worm wheel 23 which is driven by a worm 24 (Fig. 3) on a shaft 25 driven from the electric motor 10 above referred to. The brace 5^a of the stationary frame carries a bearing 26, Fig. 6, which is the main bearing for the shaft 17. This brace carries also an upper bearing 27 which supports a shaft 28 on which are carried certain guide rollers 29 in pairs, one pair for each pair of channels 13. Suitable adjustments are of course provided for the bearings 26 and 27.

The pinions 16 carry rollers or bearing rings 30 at their sides with shoulders or circumferential surfaces 31 which are exactly on the pitch circle of the pinions and these shoulders support the operating strut 11 at the lower edges of the channels 13, the faces 32 of which are likewise on the pitch line of the racks. This is a useful feature of the invention in that as the rack is reciprocated there is no friction between the bear-

ing parts 31 and 32 since both of these travel at the same rate, neither sliding with reference to the other. This method of supporting the rack is separately advantageous, and 5 is particularly advantageous in connection with the other features referred to herein. The rollers 30 are proportioned to carry the weight of the members 13 and connected parts in all of their positions during the 10 movement of the span, and the shaft 17 is proportioned to carry the load of the rollers, as well as the stresses of the pinion tooth pressures required for operation.

The rollers 29 are holding down rollers of 15 the several channels 13. And if we regard these several channels as a single member, we may consider the rollers 29 as a single roller, since they are on a common axis and serve to hold down the several parts which 20 carry the racks, and to hold the rack teeth in engagement with the pinions 16. And, instead of two pairs of struts 13 straddling the frames and balancing the pressures, and two pairs of holding-down rollers 29, a single 25 strut, pinion and roller may be used for each truss, the trusses being properly braced to carry the eccentric application of the operating strut loads. Or a single strut and operating pinion and holding-down roller could be used for the entire span, connected 30 at a point between the two trusses.

We have introduced a further improvement in the location of the holding-down roller 29 and in the shape of the operating 35 strut or rack bar (in which term we include the rack proper and the parts in which it is mounted). The outer or load-carrying end travels through an arc 33, Fig. 3, in opening the bridge, this being an arc about the center 40 of the pivot 2. The load-carrying end thus rises and falls causing an oscillation of the bar as it is moved longitudinally by the pinion.

Fig. 4 shows the extreme angular positions 45 of the bar. If the depth of the bar, or the channels 13, were the same from end to end then its oscillation would cause a variation in the length of the portion of the bar lying on the imaginary line 34 between the centers 50 of the pitch circle 31 on which it bears at one side and the holding-down roller 29 which it should just clear at the other side, and the bar would bind in some positions or be too loose in other positions.

55 We may limit this effect to a minimum by setting the holding-down roller 29 slightly back of the vertical through the center of the bearing rings 30 and to such an extent that the line 34 will be normal to the length 60 of the bar in the half way position of its oscillation; so that the departure from the normal will be the same for the starting position as for the opposite extreme angular position shown at 11^a, Fig. 4. In these extreme 65 positions the bar will occupy the max-

imum distance between the two rollers, and in the half angle between these two positions it will occupy the minimum distance.

To allow for this variation we may make the bar of a height which varies at different 70 points in its length, so that for all angular positions it will occupy the same distance on the line between the bearings above and below it. This distance is such that, with a slight allowance for mechanical inaccuracies, 75 the bar will always be prevented from coming out of proper engagement with the operating pinion but will not bind between the two rollers.

We prefer to make the bar straight along 80 the lower edge, curving the upper edge to secure the necessary variation in depth, though either or both edges may be curved with the same effect. And we prefer to secure the curvature by the use of a separate 85 strip on top of the rack bar. Figs. 5 and 6 show this most clearly. On the top of each of the channels 13 is a strip of metal 35, the top of which is adapted for engagement, 90 with the slight clearance shown, by the tread of the rollers 29. The upper edge of the strip 35 is on the curve (Fig. 5) calculated to maintain the distance between the top and bottom bearings of the bar. The exact curve followed will depend upon the special circumstances of the case such as the location of the opposite bearings and the length of the 95 rack bar and the extent of vertical movement of its load end.

Fig. 7 illustrates an arrangement in which 100 a single operating strut is used for each truss of the moving span, each strut being connected to its truss by a pin extending laterally so as to carry the strut in a plane alongside of that of the truss. The shaft 17 105 in this case also projects sidewise from the supporting member 5^a of the fixed frame. The single pinion 16 is mounted on the reduced outer end of the shaft and has a sleeve portion which carries one of the bearing 110 rings 36, while the other bearing ring 37 is mounted directly on a part of the shaft 17. The rings 36 and 37 have their outer surfaces of the same diameter as the pitch diameter of the pinion 16 and they form bearings for the plates on the lower edges of the 115 girders 38 between which is mounted a rack 15 driven by the pinion 16. On the tops of the girders are plates 35 of varying thickness as in the previous figures and held down by the rollers indicated diagrammatically at 29.

Fig. 8 illustrates a construction which may be preferable where the parts of the fixed 125 frame which carries the pinion and holding-down rollers may be separated to allow the rack bar to pass between them and thus secure an arrangement of the pinion between two bearings. The parts 5^b in this case are 130 the parts of the fixed support corresponding

to 5^a in Fig. 1. They carry bearings for the shaft 17 of the pinion and for the upper shaft 28 of the holding-down rollers. The strut is composed of two channels 13 as in Fig. 6 carrying between them the rack 15 in engagement with the pinion 16, and their lower flanges bear on rings 39 which are fixed on the pinion and correspond in diameter to the pitch line thereof. This figure illustrates a modification in the design of the upper bearing of the rack bar. On the face of each of the channels 13 there is mounted an angle 40 of light steel which is bent so that its upper flange follows the desired curved contour. The curvature is comparatively slight. By punching the web of the angle along the appropriate line it can be bolted or riveted to the channel 13 and at the same time bent to the desired contour.

Figs. 9 and 10 illustrate a construction embodying some, but not all, the features of our invention. Here the rack bar comprises a pair of channels 13 as in Figs. 5 and 6, with a rack 15 between them engaging the pinion 16. The rings 39 constitute the lower bearing for the rack bar, as in previous figures, but the upper bearing is provided with two rollers 41 and 42 located at different points in the length of the bar and mounted in triangular brackets 43 which are arranged to pivot about the shaft 17. Thus when the rack bar oscillates the frames 43 will oscillate with it and the two rollers 41 and 42 will hold it down. Heretofore rack bars of this sort have been supported on the underside by two rollers, one in advance of the operating pinion and one in rear thereof arranged on a rocking frame to accommodate the oscillation of the bar, thus requiring three bearings (for the pinion and the two supporting rollers respectively) in line along the underside of the bar, and these bearings have occupied considerable space and required a rather complicated framework to carry them and at the same time avoid interference with the fixed supporting structure. We have secured a more compact, simpler and better construction by arranging the bearings for the underside of the bar at points axially in line with the pinion. This makes it possible to use a shorter rack, which cuts down the cantilever load of the rack on the pinion and bearings when the span is open. It also carries the weight of the operating strut more directly to the supports than was the case with the prior constructions.

By making these bearings of the same diameter as the pitch circle of the pinion, there is the added advantage that the rack bar will roll on these bearings without any sliding or frictional resistance. Thus these bearing rings may be of the simplest construction. Where the bearing surfaces cannot conveniently be arranged to correspond with the pitch circle of the pinion, they may

still be arranged on the axis of the pinion by making them in the form of rollers capable of rotary movement with respect to the pinion. This has the disadvantage of requiring bearings to facilitate the turning of the bearing rollers, but it preserves the advantages of location referred to above and may be substituted for the pitch line bearings in any of the arrangements described herein. And it will be understood that any usual or suitable method of support on the underside of the rack bar may be adopted in connection with the fixed guide roller at the top and the rack bar of varying height along its length. In this case, even with a rocking supporting frame below, we avoid the necessity of side plates extending upward such as have been necessary previously to carry the movable holding-down roller.

The construction in detail may be varied considerably, the bearing rings may be bolted to the pinions as in Fig. 6, or may be shrunk on to the hubs of the pinions as in Figs. 7 and 8 or fitted direct to the shaft as at 37 (Fig. 7) or indeed may be formed directly on the shaft. Flanges may be provided as illustrated on the rollers or plates or other means used to guide the parts with a minimum lateral movement. The described bearings for the operating bar may be used with an operating pinion as described or with various other devices for reciprocating the bar.

Though we have described with great particularity of detail certain embodiments of our invention, yet it is not to be understood therefrom that the invention is restricted to the particular embodiments disclosed. Various modifications may be made by those skilled in the art without departure from the invention as defined in the following claims.

What we claim is:

1. An operating mechanism of the character described comprising an oscillating rack bar and a pinion, said rack bar being supported at its lower edge, and a holding-down device adapted to engage its upper edge, the depth of the rack bar varying at different points in its length so as to maintain its upper edge in operative relation to said holding-down device in all positions of the bar.

2. An operating mechanism of the character described comprising an oscillating rack bar and a pinion, supporting means for said rack bar located axially in line with the pinion and a holding-down device adapted to engage the upper edge of the rack bar, the depth of the rack bar varying at different points in its length so as to maintain its upper edge in operative relation to said holding-down device in all positions of the bar.

3. An operating mechanism of the char-

- acter described comprising an oscillating rack bar and a pinion, a supporting roller for the lower edge of the rack bar in line with the pinion and having a bearing surface 5 of the same diameter as the pitch diameter of the pinion and a holding-down device adapted to engage the upper edge of the rack bar, the depth of the rack bar varying at different points in its length so as to maintain 10 its upper edge in operative relation to said holding-down device in all positions of the bar.
4. An operating mechanism of the character described comprising an oscillating rack bar and a pinion and a bearing for the lower edge of said bar located axially in line with the pinion, a fixed holding down device and a strip secured to said bar shaped to engage said device in all positions of the 20 bar.
5. An operating mechanism of the character described comprising an oscillating bar, means for reciprocating the same and a bearing for the lower edge of said bar, said bearing being fixed against lateral movement and a fixed member constantly engaging the upper edge of the bar during its reciprocating movements.
6. An operating mechanism of the character described comprising an oscillating bar, means for reciprocating the same, a bearing for the lower edge of said bar, said bearing being fixed against lateral movement, and a holding-down device adapted 30 to engage the upper edge of the bar, the depth of the bar varying at different points in its length so as to maintain its upper edge in operative relation to said holding-down device in all positions of the bar.
7. A bascule bridge in combination with an operating bar for the movable span thereof, means for reciprocating said bar, a bearing for the lower edge of said bar, said bearing being fixed against lateral movement, and a fixed holding-down device 40 adapted to engage the upper edge of the bar, the depth of the bar varying at different points in its length so as to maintain its upper edge in operative relation to said holding-down device in all positions of the 50 bar.
8. A bascule bridge in combination with a rack bar for operating the movable span thereof, a pinion for reciprocating said bar, a bearing for the lower edge of said bar located axially in line with the pinion having a diameter equal to the pitch diameter of the pinion and a fixed holding-down device adapted to engage the upper edge of the rack bar, the depth of the rack bar varying at different points in its length so as to maintain its upper edge in operative relation to said holding-down device in all positions of the bar.
- In witness whereof, we have hereunto 60 signed our names.
